(57) **CLAIM**

The ornamental design for a vehicle display and control element, as shown and described.

DESCRIPTION

FIG. 1 is a rear perspective view of a vehicle display and control element;

FIG. 2 is a front perspective view thereof;

FIG. 3 is a front elevation view thereof;

FIG. 4 is a rear elevation view thereof;

FIG. 5 is an elevation view thereof from the right side;

FIG. 6 is an elevation view thereof from the left;

FIG. 7 is a top plan view thereof; and,

FIG. 8 is a bottom plan view thereof.

The portions of the vehicle display and control element shown in broken lines are for illustrative and environmental purposes and form no part of the claimed design.
